GEORGE W. KORN, OF LITTLE VALLEY, NEW YORK.

DESIGN FOR A HANDLE FOR RAZORS OR SIMILAR ARTICLES.

43,405.

Specification for Design.

Patented Dec. 31, 1912.

Application filed June 3, 1911. Serial No. 631,137. Term of patent 7 years.

To all whom it may concern:

Be it known that I, GEORGE W. KORN, a citizen of the United States, residing at Little Valley, in the county of Cattaraugus and State of New York, have invented a new, original, and ornamental Design for Handles for Razors or Similar Articles, of which the following is a specification, reference being had to the accompanying drawing, forming part thereof.

Figure 1 is a view in side elevation of the handle, and Fig. 2 is a view in edge elevation of the handle.

The design of the handle member consists of a series of pairs of parallel strips or lines,

the pairs being spaced apart, and another series of pairs of parallel strips or lines crossing the first series and both series being oblique to the longitudinal center line of the handle member, and less prominent strips or lines between the pairs of lines of each series whereby a flat effect is produced.

I claim:

The ornamental design for a handle for razors or similar articles, as shown and described.

GEORGE W. KORN.
